RADIATOR CURTAIN

Willard O. Twombly, Jackson, Mich., assignor,
by mesne assignments, to Jeffrey N. Collins,
Jackson, Mich.

Application January 19, 1934, Serial No. 707,406

3 Claims. (Cl. 123—174)

This invention relates to a temperature controlling system for automotive engines and more particularly to such a system wherein the motive power is obtained from the pressure lubricating oil of the engine.

The usual practice in the automotive industry has been to control the temperature of automotive engines by thermostatically controlled shutters located in front of the radiator. With the advent of the grilles front radiators, problems in structural design made it inadvisable to use the ordinary form of shutter and as a result automotive engines are appearing without shutters of any description.

An object of this invention is to provide a system for operating a rolled curtain which may be raised or lowered in the front of an automotive engine radiator.

Another object of this invention is to provide a mechanism for operating the curtain.

Another object of this invention is to provide a thermostatically controlled roller curtain for automotive engine radiators.

A further object of this invention is to provide a thermostatically controlled system, powered by the pressure lubricating oil of the engine, to raise and lower the curtain.

These and other objects will be apparent from the following specification when taken with the accompanying drawings, in which

Fig. 1 is a side elevation of an automotive engine equipped with a rolled curtain and the operating mechanism therefor.

Fig. 2 is a front elevation of a radiator equipped with a curtain.

Fig. 3 is an enlarged side elevation showing details of the curtain moving mechanism.

Fig. 4 is a vertical section of the thermostatically controlled oil valve.

Fig. 5 is a vertical section of the curtain operating pressure oil actuated motor and associated parts.

Fig. 6 is a broken section of the exhaust oil return valve, and

Fig. 7 is a perspective view of the movable piston pulley bracket.

Referring to Figs. 1 and 2 of the drawings, 1 is the radiator of an automotive engine provided with the usual grilles front 2. A roller curtain 3, attached at one end to the bottom 4 of the radiator is rolled on the roller 5. The roller 5 is rotatably mounted on the shaft 6 rigidly connected to the blocks 7 which are clamped to the endless sprocket chains 8. Coiled about the shaft 6 and connected at one end thereto is a spring 9. The

other end of the spring 9 is connected to the roller 5. The sprocket chains 8 are carried by sprocket wheels 10 and 11 which are fixed to shafts 15 and 16 respectively.

The shaft 16 extends across the front of the radiator to synchronize the movement of the two chains 8. Coiled about the shaft 16 is a spring 17 fixed at one end thereto and at the other end to the frame 18. The spring 17 tends to give a rotary movement to the chains 8 to carry the roller 5 upwardly. A flexible cable 19 is fixed to one of the chains 8 and when drawn upwardly results in a lowering of the roller 5 which then rolls up the curtain 3, due to the action of the spring 9. When the tension in the cable 19 is released the spring 17 on the shaft 16 rotates the chains 8 to carry the roller 5 upwardly and the curtain 3 is payed off to cover the front of the radiator 1.

The cable 19 is put under tension by the pressure oil operated motor 20, oil under pressure being supplied by the oil pump 21 of the engine lubricating system. Oil is conducted from the pump 21 by the conduit 22 to the thermostatically controlled valve 23. As shown particularly in Fig. 4, the thermostatically controlled valve 23 is mounted on the cylinder head or like part of the engine by a stud 24. The valve body 25 is mounted on a casing 26, having located therein a bimetallic element 27. The bimetallic element 27 is adapted to engage with the plunger 28 provided with an annular groove 29. The plunger 28 is normally urged downwardly by a spring 30 acting against a plug 31. As the bimetallic element 27 heats it rises to the position shown in full lines in the drawings and forces the plunger 28 upwardly bringing the groove 29 into alignment with the conduit 22 entering one side of the body 25 and the conduit 32 in alignment with the conduit 22, leaving the other side of the body 25. Thus, when the engine reaches a predetermined temperature, oil under pressure passes through the thermostatically operated valve 23, and conversely, when the engine cools to a predetermined temperature, the passage of oil through the valve 23 is cut off. The casing 26 communicates with the crank case 33 of the engine through a conduit 34 tapping into the return conduit 35. This communication permits the free movement of the plunger 28 and the escape of oil which may seep past the plunger 28.

Oil from the valve 23 is conducted therefrom by the conduit 32 to the casing 40 and thence through the feed conduit 41 to the motor 20. The motor 20 as particularly shown in Fig. 5 has

a cylinder 42 supported by base casting 43 bolted to the back wall 44 of the engine housing. The base casting 43 is provided with a vent 45 which communicates with the atmosphere to permit free movement of piston 46. The piston 46 is slidably fitted within the cylinder 42 and carries two leather or the like washers 47. A suitable closure 49 is provided for the other end of the cylinder 42. Connected to the piston 46 and slidably fitting through the closure 49 is a connecting rod 50. The feed conduit 41 enters the cylinder 42 at 52. The free end of the connecting rod 50 has attached thereto a bracket 53 shown particularly in Figs. 3 and 7. The bracket carries a freely rotating pulley 54 over which is passed the flexible cable 19. One end of the cable 19 is anchored to the frame 55, the cable passing over the sheaves 54 and 56 and the other end being connected to one of the chains 8 by the clamp 57. When oil is admitted to the motor 20 it forces the piston 46 to the right which in turn carries to the right the connecting rod 50. The movement is transferred to the pulley 54 which draws the cable 19 and which in turn lifts the chain 8. Lifting of the chain 8 lowers the roller 5, which, due to the action of the spring 9, rolls up the curtain 3 and uncovers the front of the radiator 1. Should the temperature of the engine continue to rise the thermostatically operated valve 23 remains open permitting additional oil to be forced into the motor 20. The curtain 3 will then continue to be lowered and at the time that the piston 46 of the motor 20 reaches the end of its stroke the curtain 3 will have reached the bottom of the radiator 1.

In the event that it is desirable to open the curtain by manual operation a dash rod 60 is provided, fitted in the dash 61. The rod 60 slidably fits in and is adapted to engage the extension 62 on the bracket 53. By pulling out the rod 60 the connecting rod 50 is moved to the right and the curtain is lowered in the same manner as by the oil operation.

When the temperature of the engine is lowered and the supply of pressure oil is cut off by the thermostatically operated valve 23, the curtain 3 should be raised to cover the front of the radiator. This operation is accomplished by a spring 65 connected to the bracket 53 and the frame 55. The spring 65 draws out the piston 46, which results in a slackening of the cable 19. The spring 17 on the shaft 16 then is able to lift the roller 5 by rotating the chains 8 and the curtain 3 is payed from the roller 5 to cover the front of the radiator 1. The spring 65 may be dispensed with, if desired, and the operation accomplished solely by the action of the spring 17.

Before the piston 46 will return to its left position the oil in the cylinder 52 must be released. This oil is returned to the crank case 33 by means of the one way return valve 66, shown in detail in Fig. 6. The valve 66 comprises a casing 40 and a plunger 67 urged in a direction contrary to the flow of pressure oil by the spring 68. Pressure oil flowing through the conduit 32 enters the casing 40 and strikes the plunger 67. The

plunger is moved back against the action of the spring 68 and oil under pressure flows through the feed conduit 41 to the motor 20. Oil under pressure is prevented from escaping to the return conduit 35 by the closing off by the plunger 67, 5 of the auxiliary conduit 69, leading from the feed conduit 41 to the casing 40. When the oil under pressure is cut off by the thermostatically operated valve 23 the plunger 67 is forced to the right (in Fig. 6) by the spring 68, as shown 10 in dotted outline, and a through passage is opened from the motor 20 to the return conduit 35. It should be observed that a possibility of a fluid lock due to the oil within the system preventing movement of the plungers 67 to the 15 right does not exist due to the leakage which will exist as a result of commercial tolerances in manufacture.

It will be evident from the foregoing specification that the bimetallic element 27 may be set for 20 any predetermined temperature to maintain the engine at a temperature necessary for greatest operating efficiency. While only a single modification of the invention has been disclosed it is apparent that other and equivalent mechanisms 25 may be used to actually move the curtain and it is not intended that I be limited except by the scope of the following claims.

I claim:

1. In a device of the character described for association with the radiator of an engine, a rollable curtain adapted to be rolled and unrolled in front of said radiator, one end of said curtain being fixed and the other end being rolled on a movable roller, a pair of endless flexible supports mounting said roller, means within said roller tending to rotate in one direction, and means to move said flexible supports whereby the curtain is payed from said roller to cover said radiator. 30

2. In a device of the character described for association with the radiator of an engine, a flexible web adapted to control the flow of air through said radiator, an actuating device, a frame for said radiator and said engine, two pairs of rotatably mounted sprocket wheels on said frame, the wheels of each pair being in alignment, and one wheel of each pair being rigidly mounted on a single rotatable shaft, an endless chain mounted on each pair of aligned sprocket 45 wheels, a roller mounted for rotation on and between said chains said roller supporting one end of said flexible web, the other end of said web being fixed to said frame, means within said roller tending to rotate it in one direction to wind 50 up said flexible web and an operative connection between said actuating device and one of said chains. 55

3. The invention as defined in claim 2 wherein in said operative connection comprises a connecting rod, a loose pulley mounted on one end of said connecting rod and a flexible member fixed at one end to said frame, passing over said loose pulley and fixed at the other end to one of said chains. 60
